UNITED STATES PATENT OFFICE.

GUSTAVE J. LANG, OF WEEHAWKEN, NEW JERSEY, ASSIGNOR TO AMERICAN BOSCH MAGNETO CORPORATION, OF SPRINGFIELD, MASSACHUSETTS, A CORPORATION OF NEW YORK.

AUTOMATIC TIMING MECHANISM FOR OSCILLATING MAGNETOS.

1,399,777.

Specification of Letters Patent. Patented Dec. 13, 1921.

Application filed April 8, 1919. Serial No. 288,611.

To all whom it may concern:

Be it known that I, GUSTAVE J. LANG, a citizen of the United States, residing at Weehawken, in the county of Hudson, State of New Jersey, have invented certain new and useful Improvements in Automatic Timing Mechanism for Oscillating Magnetos; and I do hereby declare the following to be a full, clear, and exact description of the invention, 10 such as will enable others skilled in the art to which it appertains to make and use the same.

The present invention relates to automatic timing mechanism for oscillating magnetos, 15 and particularly for association with slow speed engines such as are used for stationary purposes on farms, the magneto being of the high tension type for use with a jump spark plug, or of the low tension type with a make 20 and break spark plug associated with the magneto or separate therefrom, as desired.

Heretofore it was customary to crank the engine and trip the magneto manually when the piston of the cylinder to be fired was in 25 retarded position with the priming mixture compressed therein, the magneto being actuated thereafter by the engine in fully advanced position, or the reciprocating actuating lever of the engine being adjusted gradually 30 by hand or automatically to the timing position according to the speed. I have found, however, that, particularly with slow speed engines of this kind, ignition at fully retarded position is desirable for the first few 35 power impulses, instead of the first one only, whereas fully advanced ignition is proper, or at least satisfactory, at all times thereafter, even if the engine has but one cylinder. Furthermore, if the engine slows down on 40 account of overload, even to half its normal speed, fully advanced ignition is preferable to ignition at some intermediate position.

In accordance with this part of my invention, the arrangement is such that the ignition is fully retarded for the first few power impulses, sufficient for the engine to reach a suitable fraction of its running speed, and then changes automatically to fully advanced position without any intermediate position, 50 the magneto being tripped at the outset by hand or automatically by the engine, as desired.

Whether or not the timing is automatically

advanced in a single step from fully retarded to fully advanced position while starting the 55 engine, my invention also comprehends the provision of a centrifugally-responsive actuating member co-operative directly with the trip lever of the magneto to produce automatically retarded ignition in starting and 60 permit advanced ignition in running.

My invention also comprehends as another of its parts means for increasing the distortion of the oscillating springs in starting, whereby an increased sparking voltage is 65 generated to ignite the comparatively cold mixture usually present in the cylinder or cylinders at that time.

Although the aforesaid features may be utilized separately or in various combinations within my invention for automatic timing mechanism for oscillating magnetos, I describe hereinafter as the preferred embodiment an arrangement in which all the features are conjointly applied. In that specific embodiment, a trip actuator is fixed in position on a moving part of the engine to trip the magneto at fully advanced position of the engine, whereas a pivoted member has an operative position in starting to effect 70 fully retarded ignition by preventing the return movement of the trip lever of the magneto until after a sufficient angle of rotation beyond the position of actuation by the fixed actuator, and an inoperative position to 75 which it is swung by centrifugal force effective on it at the speed at which the fully advanced ignition attained by the fixed actuator becomes satisfactory in the period of the engine's operation. More specifically a pin 80 carried by an engine driven gear is positioned to trip the oscillating springs of the magneto at fully advanced position of the engine, after deflecting it to a position at 85 which the springs are distorted to their stressed condition for snapping the magneto through its generating period. A member pivoted on the gear comprises a curved arm, and a depending weighted portion. The arm is adapted to overlie the pin to form a trip 90 actuator extending rearwardly from the pin to the point of fully retarded position of the engine, the trip lever being held in an abnormally deflected position to give an increased distortion of the oscillating springs until it 95 snaps over the rear end of the arm. The 100 105

weighted portion is calibrated to swing the curved arm to its inoperative position out of the path of rotation intercepted by the trip lever at a speed predetermined according to 5 the value from which the engine satisfactorily continues its acceleration to normal running speed with the fully advanced ignition thereafter effected by the pin.

In order that the pivoted member will not 10 swing gradually away from the pin to its inoperative position until that predetermined speed is reached, I prefer to provide a latch for lightly holding the arm against the pin until overcome by the centrifugal force effective 15 at that speed on the weighted portion. In this way, I avoid the additional noise and shock that would otherwise be incidental to starting the engine due to the arm first striking the trip lever and then the pin.

20 Also I prefer to provide a curved trip lever on the magneto and to round off the actuating edge of the pivoted arm so that the noise and shock when the lever is struck at the beginning of its deflecting movement in 25 the starting period are reduced as a result of the combined rolling and sliding action between them. Likewise I prefer to use a round pin, either carrying a roller or being of one piece, to give the same effect in coöperating with the curved trip lever during 30 running.

As a further refinement, I prefer to provide a manually detachable latch for holding the pivoted member when it is swung to 35 inoperative position. There is then less possibility that the pivoted member will, as a result of some unexpected cause, swing to its fully retarded position while the engine is running.

40 In the accompanying drawings illustrating this preferred embodiment of my invention in which, as an example, the timing mechanism is mounted on a half-time gear of a single-cylinder four-cycle engine,

45 Figure 1 is a side view of the engine, partly broken away, showing a high tension magneto and the tripping mechanism therefor; Fig. 2 is an end view thereof; and Fig. 3 is similar to Fig. 1 except that it shows the oscillating springs in distorted position just ready to trip.

50 The pinion 1 on the engine crank shaft 2 is meshed with a half-time gear 3. That gear has a pin 4 fixed to it so as to rotate in the path intercepted by the trip lever 5 of the high tension magneto 6 having the oscillating springs 7.

55 The pivoted member loosely mounted on the stud 8 comprises a curved arm 9 and a weighted portion 10 depending therefrom, so as to move, in response to centrifugal action upon rotation of the gear, from its position of rest in starting shown in full lines to its position of deflection in running 60 shown in broken lines. In the starting posi-

tion, the curved arm 9 abuts against and overlies the pin 4, extending rearwardly thereof. In the running position, the arm 9 occupies a position entirely out of the path 70 intercepted by the trip lever 5.

The trip lever 5 is adapted to be deflected by the curved arm 9 to the position shown in full lines in Fig. 3, whereupon the oscillating springs 7 are distorted and held in distorted position until the trip lever passes 75 beyond the trailing end of the arm. The springs, then stressed, snap the armature of the magneto through its generating period. However, when the curved arm 9 is swung to its operative position, the trip lever 5 is 80 deflected by the pin 4 to the position indicated by the broken lines in Fig. 3, the oscillating springs 7 then being distorted to a lesser degree and snapping over the pin at a slightly reduced speed. The sparking voltage 85 generated upon oscillation of the armature from the position to which it is deflected by the pin 4 is sufficient to generate a satisfactory spark at the gap of a high tension spark plug in the cylinder of the engine 90 when the engine is running. At starting the more intense spark required for ignition of comparatively cold mixture is produced as a result of the increased distortion of the 95 springs by the curved arm then overlying the pin.

The pin 4 is so positioned as to release the trip lever 5 at fully advanced ignition of the engine, whereas the arm 9 has sufficient circumferential extent to hold the trip lever 100 in deflected position until fully retarded ignition is reached. The weighted portion 10 of the pivoted member may be so calibrated as to swing the arm 9 to its inoperative position when the engine attains about 105 half its normal running speed. I have found in many cases that about half speed is not reached until the engine has received several power strokes, and at about that speed the ignition may be changed in a single step 110 from the fully retarded position to the fully advanced position with satisfactory results in operation.

115 The actuating edge 11 of the pivoted member is round, and likewise the pin 9 is round, so that the action of either of them with the curved trip lever 5 in distorting the springs 7 is rolling as well as sliding. Thus the noise and shock of the engagement between them, in starting as well as in running, is reduced. 120

Attached to the curved arm 9 is a spring clip 12 adapted to lightly hold the pivoted member in operative position, the centrifugal action effective on the weighted portion 10 being sufficient at the change-over 125 speed desired to disengage the latch in addition to swinging the arm to its inoperative position. In this way, the arm is prevented from occupying an intermediate position in which it would first strike the trip lever 5 130

and then the pin 4, thus obviating unnecessary noise and shock at some of the ignition periods in starting.

The spring clip 13 catches the pivoted member and disengageably holds it, until released by hand, whenever it is thrown over to inoperative position, so that it cannot swing back as a result of some unexpected cause.

10 To start the engine from rest, the pivoted member is unlatched by hand from the spring clip 13, whereupon it turns to the position in which the curved arm 9 overlies the pin 4. If necessary, the cylinder is primed. Smaller engines may then be cranked by hand, the charge being compressed as the engine is turned over dead center, whereupon the magneto will be operated and the mixture ignited. If the engine 15 starts into action under its own power, the curved arm 9 remains latched by the spring clip 12 until about half normal speed is attained, during which time several power impulses are gone through. As soon as the 20 pivoted member responds to the centrifugal action effective on the weighted portion 10, the ignition occurs at the fully advanced position as a result thereafter of the actuation of the trip lever 5 by the pin 4 instead 25 of by the curved arm 9.

If, however, the engine is too powerful to be turned completely over, the trip lever 5 may be cocked by hand in a deflected position and the engine turned past dead center 30 with the inlet valve open. Then after the cylinder is primed, the fly wheel may be rocked to compress the mixture and the trip lever released by hand at the proper moment. Or, the engine may be started by a battery 35 ignition system after the priming mixture is compressed in the cylinder.

Having thus described my invention, what a claim is:

1. The combination with an internal combustion engine, of ignition generating apparatus therefor comprising an oscillating magneto, and means for oscillating said magneto in fully retarded or advanced positions, said means comprising means automatically actuated by said engine for changing the period of actuation of the oscillating means from full retard to full advance in a single step.

2. The combination with an internal combustion engine, of ignition generating apparatus therefor comprising an oscillating magneto, and means for oscillating said magneto in retarded and advanced positions for several consecutive power strokes 55 for starting the engine and for normal running operation of the engine respectively, said means comprising means actuated by said engine for automatically changing from the fully retarded to the fully advanced position in a single step.

3. The combination with an internal combustion engine, of ignition generating apparatus therefor comprising an oscillating magneto having a trip lever, and centrifugally-responsive actuating mechanism 70 which, at starting, is positioned to actuate the trip lever at a retarded position and which, at running, is positioned in an inoperative position.

4. The combination with an internal combustion engine, of ignition generating apparatus therefor comprising an oscillating magneto having a trip lever, and centrifugally-responsive actuating mechanism, which, for several consecutive power strokes 80 in starting, is positioned to actuate the trip lever at retarded position and which, immediately thereafter, is positioned in an inoperative position.

5. The combination with an internal combustion engine, of ignition generating apparatus therefor comprising an oscillating magneto having a trip lever, an actuating member fixed in position on a moving part of the engine for actuating the trip lever 85 at an advanced position, and centrifugally-responsive actuating mechanism which, at starting, actuates the trip lever at a retarded position and which, at running, assumes an inoperative position. 95

6. The combination with an internal combustion engine, of ignition generating apparatus therefor comprising an oscillating magneto having a trip lever, centrifugally-responsive actuating mechanism which, at 100 starting, actuates the magneto at a retarded position and which, at running, assumes an inoperative position, and disengageable means lightly holding said mechanism in its starting position. 105

7. The combination with an internal combustion engine, of ignition generating apparatus therefor comprising an oscillating magneto having a trip lever, an actuating member fixed in position on a moving part of the engine for actuating the magneto at an advanced position, a centrifugally-responsive actuating member which, at starting, actuates the magneto at a retarded position and which, at running, assumes an inoperative position, and a latch lightly holding the centrifugally-responsive member in its starting position. 110

8. The combination with an internal combustion engine, of ignition generating apparatus therefor comprising an oscillating magneto having a trip lever, centrifugally-responsive actuating mechanism which, at starting, actuates the magneto at a retarded position and which, at running, assumes an inoperative position, and disengageable means lightly holding said mechanism in its inoperative position. 115 120

9. The combination with an internal combustion engine, of ignition generating ap- 130

- paratus therefor comprising an oscillating magneto having a trip lever, an actuating member fixed in position on a moving part of the engine for actuating the magneto at an advanced position, centrifugally-responsive mechanism which, at starting, actuates the magneto at a retarded position and which, at running, assumes an inoperative position, and a latch lightly holding the centrifugally responsive member in inoperative position.
10. The combination with an internal combustion engine, of ignition generating apparatus therefor comprising an oscillating magneto having a trip lever, an actuating member fixed in position on a moving part of the engine for actuating the magneto at an advanced position, centrifugally-responsive mechanism which, at starting, actuates the magneto at a retarded position and which, at running, assumes an inoperative position, disengageable means lightly holding said mechanism in its starting position, and disengageable means lightly holding said mechanism in its inoperative position.
11. The combination with an internal combustion engine, of ignition generating apparatus therefor comprising an oscillating magneto having a trip lever and an oscillating spring, an actuating member fixed in position on a moving part of the engine for actuating the magneto at an advanced position, and means connected to and actuated by a movable part of said engine for moving said trip lever to an abnormally deflected position to abnormally distort the spring.
12. The combination with an internal combustion engine, of ignition generating apparatus therefor comprising an oscillating magneto having a trip lever and an oscillating spring, an actuating member fixed in position on a moving part of the engine for actuating the magneto at an advanced position, and a centrifugally-responsive actuating member overlying the fixed actuating member at starting.
13. The combination with an internal combustion engine, of ignition generating apparatus therefor comprising an oscillating magneto having a trip level and an oscillating spring, an actuating member fixed in position on a moving part of the engine for actuating the magneto at an advanced position, and a centrifugally-responsive actuating member which, in starting, overlies the fixed actuating member and abnormally distorts the spring.
14. The combination with an internal combustion engine, of ignition generating apparatus therefor comprising an oscillating magneto having a trip lever, a pin fixed in position on a rotating part of the engine for periodically tripping the magneto at an advanced position, and a pivoted member having an arm adapted to overlie the pin to hold the trip lever in an abnormally deflected position until the engine reaches a retarded position in starting, and also having a weighted portion adapted to swing the arm to an inoperative position when the engine attains a predetermined speed.
15. The combination with an internal combustion engine, of ignition generating apparatus therefor, comprising an oscillating magneto having a trip lever, a pin fixed in position on a rotating part of the engine for actuating the magneto at an advanced position, a pivoted member having an arm adapted to overlie the pin to hold the trip lever in a deflected position until the engine reaches a retarded position in starting and also having a weighted portion adapted to swing the arm to an inoperative position when the engine attains a predetermined speed.
16. In an oscillating magneto, a curved trip lever, and a curved centrifugally responsive actuator with a rounded actuating part having a rolling and sliding action with the trip lever in deflecting it.
17. In an internal combustion engine having an ignition device comprising an oscillating magneto, the combination of oscillating means on said magneto, means actuated by said engine for operating said oscillating means in advanced timing position for the normal operation of said engine, and speed-responsive means actuated by said engine for operating said oscillating means in retarded timing position in the starting operation of said engine.
18. In an internal combustion engine having an ignition device comprising a magneto, the combination of movable ignition effecting means on said magneto, means on said engine for operating said movable means in advanced timing relation during the normal running operation of said engine and means actuated by said engine to automatically operate said movable means in retarded timing relation during the starting strokes of said engine.

In testimony whereof I affix my signature.
GUSTAVE J. LANG.
